United States Patent Office.

JONATHAN JOHNSON, OF LOWELL, MASSACHUSETTS.

Letters Patent No. 104,960, dated July 5, 1870.

IMPROVEMENT IN PADS FOR HORSES' FEET.

The Schedule referred to in these Letters Patent and making part of the same

To all whom it may concern:

Be it known that I, JONATHAN JOHNSON, of Lowell, in the county of Middlesex, in the State of Massachusetts, have invented certain new and useful Improvements in Pads for Horses' Feet, of which the following is a full, clear, and exact description, reference being had to the accompanying drawing making part of this specification, in which—

Figure 1, sheet 1, is a bottom view of the pad applied;

Figure 2 is a side elevation;

Figure 3 is a rear, and

Figure 4 is a front elevation;

Figure 5, sheet 2, is a plan of a pad, covering the whole surface of the foot and shoe;

Figure 6 is a plan of a pad, covering the frog and the sole of the foot, within the shoe.

Fig. 1, sheet 1—

A A is the toe-band.

B, the pad.

C C, the chains.

a a², the plates.

Fig. 2—

A is the band.

D, the spring.

C, the chain.

Fig. 3—

B is the pad.

E, the packing.

S S, the shoe, and

T T, the outward incline.

Fig. 4—

A is the toe-band, and

D D, the springs.

Fig. 5, sheet 2—

A A A is the toe-band.

B, the pad.

F F, the straps.

H H H H, spring clamps.

I, hook.

K K, heel-links.

Fig. 6—

A A A is the toe-band.

B, the pad.

D, the spring.

C, the chain.

d², wire.

F F, straps.

H, spring clamps.

L L, links.

P P, bars.

g², heel-spring.

In applying my improvement to some forms of horses' feet, where the soles are flat, and project downward, very little space exists for packing. In such cases, pad B, fig. 5, sheet 2, as shown, will accommodate such deformity, and support the quantity of pack-

ing required, and may be used with single or double fastenings, as shown, and applied to the toe-band.

My invention consists in an improved mode or means of holding a pad to a horse's foot, the toe-band A, made of leather, rubber, or metal, being the chief and leading object presented, as shown in figs. 1, A, 2, A, and 4, A, sheet 1, and figs. 5, A, 6, A, sheet 2, passing over the front of the hoof and shoe, connecting with the pad B, underneath the foot, for the purpose of holding it securely.

When leather or rubber are used, they may be protected from wear by metal plates a a², fig. 1, sheet 1, and is adapted for either a calked or slipper shoe.

I also connect with the pad B, (see fig. 6,) at or near the heel, with either strap F, chain C, wire d², or spring D, as may best conform to the foot, sometimes connecting the heel fastenings at the sides f f², corners M M, or center N of pad B, as shown in fig. 6, sheet 2.

Pad B, fig. 1, is substantially the same as my former patent, dated May 4, 1869, with the toe-band and heel-fastenings applied.

The toe-band A may be applied to a pad with or without the absorbent packing. The pad may cover the whole of the bottom of the hoof and shoe, or the frog and inner sole only.

Connections, shown at the heel of pad B, fig. 6, are changeable and adjustable from one point to another, as shown, and may be of any material required, in fastening as may best accommodate the foot, all having the same relation to the toe-band A.

When straps are used, I employ a spring clamp, H, fig. 5, as the straps are not weakened by cutting buckle-holes.

In fig. 6, the links L L, bars p p, heel-spring d², either are used to prevent the packing from working out when not attached to the pad.

I also represent that, in order to realize all the advantages of my invention, I change the form of the shoe at the heel, by an outward incline, T T, as shown in fig. 3, in such a manner that pressure causes a sliding action outward, making room for the expanded frog.

I consider the plain fastening shown in figs. 1, 2, 3, and 4, sheet 1, preferable, and best adapted for general use. Persons acquainted with the care of horses will readily understand its application and use.

I claim, as follows:

1. The toe-band A, and the elastic or spring connections D and F, in combination with the pad B, substantially as and for the purpose described.

2. The protecting plates a a², in combination with the toe-band A and the pad B, in the manner and for the purpose set forth.

Witnesses: JONATHAN JOHNSON.

JOHN E. CRANE,

W. R. CRANE.
